CENTRALIZED TRAFFIC CONTROLLING
SYSTEM

Neil D. Preston, Rochester, N. Y., assignor to General Railway Signal Company, Rochester, N. Y.

Application March 3, 1932, Serial No. 596,516

25 Claims. (Cl. 177—353)

This invention relates to centralized traffic control systems for railroads, and more particularly pertains to the communication part of such systems.

5 This application is a continuation in part of my prior application Ser. No. 589,186 filed January 27, 1932, and the subject matter which is common between this application and said prior application is to be claimed in this application.

10 The present invention contemplates a centralized traffic control system in which the switches and signals at a single station located along a railroad system are placed under the supervision of an operator at a central control office; and in

15 which the condition of such switches, signals and various other traffic conditions at that location will be transmitted to the control office for providing the operator with the information necessary for the governing of train movements. In

20 a system of this type, the switches and signals are associated with such automatic block signalling means as may be necessary under the particular circumstances met in practice in order that the manual control by the operator may be effected in a safe and reliable manner.

It often happens that there are several outlying track switches with their associated signals located adjacent or near each other, which traffic governing devices are preferably governed from 30 a central tower of an interlocking plant, or other office already established. Ordinarily such control would be effected over the usual direct line wire type of system, but the present invention provides a selector type system particularly adapted to an installation of this type.

The present invention more particularly relates to the communication part of such a centralized traffic control system, and proposes to provide a communication system having only two line wires 40 extending between the control office and the outlying field station. In this communication system, either control impulses are transmitted from the control office, or indication impulses are transmitted from the field station during any 45 particular operating cycle; and these impulses are made distinctive by reason of their polarity for the purpose of transmitting the desired controls or indications. To accomplish this, the system of the present invention provides that a 50 battery or other suitable source is located at each of the two locations, namely, at the control office and at the outlying field station, with the control apparatus and the circuits so arranged that irrespective of the simultaneous occurrence of control and indication conditions, only one location

or the other is effective to transmit impulses at any one time.

Irrespective of whether the control office or the outlying field station is effective to place distinctive impulses upon the line circuit, the duration of these impulses is determined in the control office. Thus, the system of the present invention simplifies the timing characteristics of that type of communication system in which outlying field stations are permitted to transmit impulses from their own local sources of energy.

These characteristic features of the present invention, thus briefly stated, will be explained more in detail in the following description of one embodiment of the invention; and various other characteristic features, functions and advantages of a system embodying this invention will be in part pointed out and in part apparent as the description progresses.

In describing the invention in detail, reference 20 will be made to the accompanying drawings, in which similar parts throughout the several views are designated by similar reference characters, and in which:

Fig. 1 illustrates the apparatus and circuit arrangements provided for a typical control office arranged according to the present invention; and,

Fig. 2 illustrates the apparatus and circuit arrangements employed at a typical field station for 30 receiving control impulses and for transmitting indication impulses to and from that field station in accordance with the present invention, and adapted to be associated with the apparatus employed in the control office illustrated in Fig. 1. 35

Although the present invention has been shown applied to the control of a single switch and its associated signals, such as used at one end of a passing siding, it should be understood that the invention is not limited, as thus shown, to the 40 control of only one switch and its signals, but may be extended for any desired number of switches and signals and may be readily applied to all types of track layouts. In the event, that a large number of switches and signals are located at the field station requiring the reception of controls and the transmission of indications, the system may be extended in any one of several ways. For example, a greater number of steps may be employed to thereby merely duplicate 50 the apparatus illustrated. Another alternative would be to divide the controls and indications into several groups, any one group of which could hold communication with the control office during any one particular operating cycle, as dis- 55

closed for example in the patent to W. D. Hailes et al., No. 170,141 issued August 22, 1939. It is understood of course that all such auxiliary features and modifications may be applied to the present invention without in any way limiting or detracting from the scope thereof.

For the purpose of simplifying the illustration and facilitating in the explanation, the various parts and circuits constituting the embodiment of the invention have been shown diagrammatically and certain conventional illustrations have been employed, the drawings having been made more for the purpose of making it easy to understand the principles and mode of operation, than with the idea of illustrating the specific construction and arrangement of parts that would be employed in practice. Thus, the various relays and their contacts are illustrated in a conventional manner, and symbols are used to indicate connections to the terminals of batteries, or other sources of electric current, instead of showing all the wiring connections to these terminals.

The symbols (+) and (−) are employed to indicate the positive and negative terminals respectively of suitable potentials, or other sources of direct current; and the circuits with which these symbols are used, always have current flowing in the same direction. The symbols (B+) and (B−) indicate connections to the opposite terminals of a suitable battery, or other direct current source which has a central or intermediate tap designated (CN); and the circuits with which these symbols are used, may have current flowing in one direction or the other depending upon the particular terminal used in combination with the central or intermediate tap (CN).

In general, the system includes a control office equipment interconnected with a field station equipment by two line wires, namely, a common line wire 10 and a control line wire 12. At the control office a tower battery TB is provided with a center tap connected to the common wire 10; and similarly, at the field station a field battery FB is provided with a center tap connected to the common wire 10. A polar line relay L⁰ at the control office has its windings included in the control line wire 12; and similarly, at the field station a polar line relay L has its windings included in the line wire 12. These line relays are of the three position biased to neutral polarized type.

Neutral selecting relays S⁰ and S are located respectively at the control office and at the field station for normally connecting the control line wire 12 to the mid tap of the respective batteries TB and FB, or in other words to the common wire 10. When the contacts of either of these relays are picked up, current impulses are then placed upon the control line wire 12 in accordance with the positions of the polar contact of its respective code sending relay. In the event that both of these selecting relays are energized at the same time, means is provided so that no impulses are transmitted until the operator in the control office has suitably intervened to eliminate the locked up condition then existing, as more specifically pointed out hereinafter. The code sending relays CS⁰ and CS are respectively provided at the control office and at the field station, these relays being of the two position polar magnetic stick type.

The control line wire 12 also includes an impulsive contact 15 in the control office operated by an impulsive relay IM, so that, whenever a

selecting relay is energized, time spaced impulses are placed upon the control line circuit having polarities as determined by the corresponding code sending relay, all of which will be more specifically pointed out hereinafter.

Control office equipment.—The control office (see Fig. 1) includes, besides the apparatus above enumerated, a quick acting line repeating relay LR⁰ of the neutral type, which repeats each energization of the line relay L⁰ irrespective of the polarity with which this line relay is energized. In other words, the quick acting line relay LR⁰ is energized each time the line circuit is energized and is deenergized between the successive impulses.

A slow acting line repeating relay SL⁰ of the neutral type is provided with such slow acting characteristics that it does not drop away between the successive energizations of the line repeating relay LR⁰, but once it is energized at the beginning of a cycle, it remains energized until after a predetermined time at the end of the cycle. Also, besides being slow releasing this relay SL⁰ is somewhat slow in picking up, although the release period is relatively long compared to the pick-up period.

A checking relay CK⁰ of the two position polar magnetic stick type is provided to register or store the particular polarity of the initiating impulse applied to the line circuit at the beginning of each cycle of operation.

Similarly, an impulse storing relay IS⁰ is provided to register or store the particular polarity of each of the impulses applied to the line circuit, so that the polarity of each impulse can be made effective during the deenergized condition of the line.

A bank of stepping relays a, b, c and d together with a half step HS⁰ serve to mark off the steps of each cycle of operation. The stepping relay bank takes one step each time the line repeating relay LR⁰ is picked up; while the half step relay HS⁰ has its contacts actuated to new positions each time the line repeating relay LR⁰ is released. This half step relay HS⁰ is of the two position polar magnetic stick type. The steps of the cycle are thus marked off so that the code sending relay CS⁰ may be distinctively positioned in accordance with the controls to be transmitted.

The impulsive relay IM cooperates with the stepping relay bank and half step relay HS⁰ in a manner to time space the impulses applied to the line circuit in accordance with the actual response of the system in the control office.

The control office equipment also includes, besides the various control relays and circuits, a control panel having a group of control levers, a miniature track layout corresponding in every way to the actual track layout in the field, and various indicating lamps or equivalent means to register the response or conditions of the apparatus at the field station.

As typical of such a control panel, a miniature track switch ts is illustrated as having associated therewith a switch machine control lever SML and a signal control lever SGL for governing the corresponding track switch and signals in the field location. A starting button SB is provided to be actuated subsequent to the proper positioning of the control levers to thereby initiate the system for the transmission of controls as then set up by the levers. The actuation of the control lever SML to one position or the other results in the normal or reverse control of the

corresponding track switch at the field station, while the actuation of the signal control lever SGL from an intermediate position corresponding to signals "at stop," to the right or left clears 5 the signals over the track switch in an east or west bound direction respectively.

A field starting button FSB provides means whereby the operator may cause the field station to transmit its indications although a change 10 in conditions at the station has not previously occurred. This field starting button FSB also provides, under certain conditions hereinafter pointed out, means whereby the operator may allow the field station to transmit although the 15 line circuits have been locked up upon the occurrence of a simultaneous start in the control office and at the field station. However, during such resulting cycle of operation for the transmission of indications from the field station, the 20 operator may depress the starting button SB and maintain it in an actuated position until another cycle of operation is initiated, thereby determining that such succeeding cycle of operation shall be for the transmission of control impulses.

25 The control machine also includes suitable indication storing relays IR¹, IR² and IR³ for storing the various indications transmitted from the field station. The indication storing relay IR¹ stores the indication of the fact of whether the 30 associated track switch is locked or unlocked as indicated by a switch repeating relay WP at the field station, while the normal or reverse position of the track switch is indicated or stored by the relay IR². The indications of these relays IR¹ and 35 IR² may be combined in such a manner that indicator lamps or other types of indicator means may be suitably controlled to inform the operator as to the actual positions of the corresponding track switch TS in the field. For the purpose 40 of illustration, the normal and reverse indicator lamps NI and RI have been shown together with a lock indicating lamp LI.

45 The indication storing relay IR³ is controlled in accordance with the occupied or unoccupied condition of the detector track section associated with the outlying track switch illustrated in Fig. 2, as repeated by a track relay T, so that an indicating lamp OS is controlled in accordance with the passage of a train.

50 *Field station equipment.*—The field station (see Fig. 2) also includes, besides the apparatus above mentioned, a quick acting line repeating relay LR which repeats the energizations and deenergizations of the line circuit as made effective by 55 the line relay L, irrespective of the polarity of the energizing impulses.

A slow acting relay SL of the neutral type repeats the energized condition of the relay LR, but is of the slow picking up and slow releasing type 60 having such characteristics that its releasing period is relatively long compared to its pick-up period so as to maintain the contacts of the relay SL in picked up positions between the successive energizations of the relay LR. In other words, 65 the relay SL is energized at the beginning of each cycle of operation and is maintained energized or picked up throughout the cycle, until the expiration of a predetermined time after the last energization of the line circuit for the cycle of operation.

70 A slow acting line repeating relay SLR has characteristics similar to those of the relay SL but repeats the combined conditions of the relays LR and SL in such a manner that the relays SL and SLR are picked up at the beginning of a

cycle of operation at substantially the same time, but at the end of a cycle of operation the releasing periods of the relays SL and SLR are cumulative.

A checking relay CK of the two position polarized type is provided to register or store the particular polarity with which the line circuit is energized during the initiating period at the beginning of each cycle of operation, while an impulse storing relay IS is provided to store the 10 particular polarity of each impulse applied to the line circuit until the application of the succeeding impulse, so that the polarity of the impulse may be made effective to execute the proper control during the following deenergized period of 15 the line circuit.

A stepping relay bank including relays 1, 2, 3 and 4 together with a half step relay HS is provided to take one step for each energization of the line repeating relay LR so as to mark off the 20 steps upon which the code sending relay CS may be distinctively positioned in accordance with the indications to be transmitted.

A track switch TS is operated by a switch machine SM of any suitable type, such for example 25 as disclosed in the patent to W. K. Howe, No. 1,466,903, dated September 4, 1923. This switch machine may, if desired, be provided with a dual control selector, as disclosed for example in the patent to W. K. Howe, No. 1,852,573, issued April 5, 30 1932, so as to permit the local manual operation of the track switch.

The position and locked condition of the track switch TS is repeated by the usual switch repeating relay WP of the polar neutral type. This relay WP is controlled by a suitable polarized circuit (not shown) including point detector contacts or suitable switch box contacts (not shown), so that the relay WP is energized with current of one polarity or the other depending upon the normal or reverse position of the track switch TS, and so that it is deenergized whenever the track switch TS is unlocked or is in operation.

The signals 1A—1B are provided for governing 45 traffic over the main track and over the turn-out track respectively in an east bound direction; while signals 2A—2B are provided for governing traffic over the main track or off the turn-out track respectively in a west bound direction. These signals have associated therewith suitable 50 automatic block signalling for providing the safe operation of trains, as shown for example in my Patent No. 2,082,462 issued June 1, 1937, all of which is unnecessary to be pointed out in detail for an understanding of the present invention.

The track switch TS has associated therewith the usual detector track section having a track battery and a track relay T. Also, preferably associated with the track switch TS is suitable approach locking and detector locking (not shown) 60 to provide the safe governing of the track switch in accordance with the traffic conditions.

The track switch machine SM is remotely governed by the operator in the control office in accordance with the position of the switch machine control lever SML, which control is locally repeated at the switch machine by the switch machine relay SMR; and similarly, the signals 1A—1B and 2A—2B are governed remotely in accordance with the signal control lever SGL, which control is repeated locally by the signal relay SR and the direction relay DR. Such local control is well understood by those skilled in the art, and has been more specifically disclosed in 70 75

the patent to S. N. Wight, No. 1,889,457, issued November 29, 1932.

A change in the condition or the position of the track switch TS is of course repeated by the relay WP, and similarly a change in the condition of the detector track section is repeated by the relay T. Such changes cause the automatic initiation of the system for the transmission of the indications as then set up. These changes are stored by change relays CH and CHS until the system has insured the transmission of the new indications.

It is believed that the nature of the invention, its advantages and characteristic features can be best understood with further description being set forth from the standpoint of typical operations.

OPERATION

The system of the present invention is normally in a condition of rest, but may be initiated into a cycle of operation either from the control office or from the field station whenever there are new controls or new indications to be transmitted. Although new controls and indications may simultaneously occur, the present invention is so arranged that only indications or controls may be transmitted during any one cycle of operation; and in such cases where they simultaneously occur, suitable means is provided so that the operator may act to allow the indications to be transmitted followed by a cycle of operation for the transmission of controls.

When a cycle of operation is initiated, a plurality of distinctive impulses (distinctive by reason of their polarity) are placed upon the line circuit for the transmission of either controls or indications. The polarity of these impulses is determined in the case of the transmission of controls in the control office; while, if indications are transmitted, the polarity is determined at the field station. In either case, the duration of the impulses and the time spacing between successive impulses is determined in the control office.

The application of the plurality of impulses for each cycle of operation causes the step-by-step mechanism to operate sequentially and in synchronism both at the control office and at the field station. The steps marked off by these step-by-step mechanisms permit the distinctive control of devices on each step in accordance with the messages transmitted by reason of the distinctive impulses. In other words, the step-by-step mechanisms are operated irrespective of the characters of the impulses, while the characters of the impulses serve to carry the proper messages.

While the system is at rest, or in a so-called period of blank, the line circuit including line wires 10 and 12 is normally deenergized. Similarly, most of the remaining relays and circuits of the system are normally deenergized with a few exceptions.

For example, the code sending relay CS⁰ in the control office (see Fig. 1) is normally energized during the period of blank from (B+), through back contacts 16, 17, 18 and 19 of stepping relays a, b, c and d respectively, wire 20, front contact 21 of a field starting button FSB, wire 22, back contact 23 of quick-acting line repeating relay LR⁰, wire 24, windings of code sending relay CS⁰, to (CN). The current which flows in this circuit is effective to actuate the polar contact of the code sending relay CS⁰ to a right hand position.

Similarly, the code sending relay CS at the field station (see Fig. 2) is normally energized during the period of blank by a circuit from (B+), through back contacts 25, 26, 27 and 28 of stepping relays 1, 2, 3 and 4 respectively, wire 29, back contact 30 of quick-acting line repeating relay LR, wire 31, windings of code sending relay CS, to (CN). The current which flows in this circuit is effective to actuate the polar contact of the code sending relay CS to a right hand position.

Also, a change relay CH at the field station is normally energized through a stick circuit closed from (+), through front contact 32 of track relay T, wire 33, front contact 34 of switch repeating relay WP, wire 35, front contact 36 of relay CH, wire 37, lower winding of relay CH, to (-).

It is, of course, understood that the detector track section associated with the track switch TS is a normally energized track circuit so that the track relay T is normally picked up.

The switch repeating relay WP is energized through a polarized circuit including suitable point detector contacts or the like, so as to be energized with current of a particular polarity in accordance with the normal locked condition of the track switch TS, thereby actuating its polar contacts to right hand positions and actuating its neutral contacts to energized or picked up positions. Whenever the track switch TS is in mid-stroke or is unlocked, the relay WP is deenergized, but when the track switch TS is in its reverse locked position, the relay WP is energized with current of the opposite polarity, thereby actuating its polar contacts to left hand positions and its neutral contacts to picked up positions. Although these circuits for the relay WP have not been shown, they will be readily understood by those skilled in the art.

The half step relay HS⁰ is normally energized during the period of blank by a circuit from (B+), through back contacts 38, 39, 40 and 41 of stepping relays a, b, c and d, wire 42, windings of relay HS⁰, wire 43, back contact 44 of relay LR⁰, to (CN). The current which flows in this circuit is effective to actuate the contacts of the relay HS⁰ to right hand positions preparing the stepping relay bank for the first or initial step of the next cycle of operation. As the half step relay HS at the field station has a normal energizing circuit substantially identical with the half step relay HS⁰ in the control office, it will not be pointed out in detail.

Transmission of controls.—Whenever the system is at rest, or in a period of blank, the operator can initiate the system for the transmission of such controls as he may desire. For example, if he desires to operate the track switch TS or to govern the signals 1A—1B and 2A—2B, he properly positions the control levers SML and SGL, and then actuates the starting button SB.

It is to be noted, that the operator may move the control levers to such positions as he may desire without the transmission of controls until such time that he actuates the starting button SB. However, such an arrangement is to be considered as merely one embodiment of the present invention, as the system might readily be arranged to be initiated upon the actuation of one or several of the control levers as shown, for example, in my Patent No. 2,159,567 issued May 23, 1939.

The actuation of the starting button SB, while the system is at rest, causes the energization of the selecting relay S⁰ by a circuit closed from

(+), through back contact 45 of the starting button SB, wires 46 and 47, back contact 48 of slow-acting line repeating relay SL⁰, wires 49 and 50, windings of relay S⁰, to (-).
 5 The energization of the selecting relay S⁰ closes a front contact included within the line circuit for completing it from the positive terminal of the battery TB, through wire 51, polar contact 52 of code sending relay CS⁰ in a right hand position, wire 53, front contact 54 of selecting relay S⁰, wire 55, windings of line relay L⁰, wire 56, back contact 57 of impulse relay IM, line wire 12 to the field station, windings of line relay L at the field station, wire 58, back contact 59 of the selecting relay S, wire 59, through the common return line 10 to the mid tap of battery TB. This initial impulse is positive in character by reason of the normal position assumed by the contact 52 of the code sending relay CS⁰, 15 and thus causes the energization of the line relays L and L⁰ in a manner which effects the actuation of their polar contacts to right hand dotted line positions.

The energization of the line relay L⁰ is in 25 turn repeated by the quick-acting line repeating relay LR⁰, by reason of a circuit from (+), through polar contact 60 of relay L⁰ in a right hand position, wires 61 and 62, windings of relay LR⁰, to (-). The line repeating relay LR 30 at the field station is similarly energized with polar contact 63 in a right hand position, through circuits obvious from the drawing.

The picking up of front contact 64 of the relay LR⁰ energizes the relay SL⁰, but as this relay is of the slow-acting type, a certain predetermined time elapses before its contacts assume picked up positions.

Similarly, the picking up of front contact 65 of the relay LR at the field station energizes 40 the slow-acting line repeating relay SL, but as this relay has slow-acting characteristics its contacts do not pick up until after a predetermined time.

The picking up of contact 66 of relay LR closes 45 a circuit from (+), through front contact 66, wires 67 and 68, windings of relay SLR, to (-), which circuit energizes this relay SLR, but, as it has slow-acting characteristics, its contacts do not pick up until after a predetermined time.

50 It is to be noted that these relays SL⁰, SL and SLR all preferably have the same slow-acting characteristics and their contacts preferably assume picked up positions at substantially the same time.

55 During the time following the energization of the line relays L⁰ and L, but preceding the picking up of the contacts of the slow-acting relays SL⁰ and SL, the checking relays CK⁰ and CK are energized with polarities dependent 60 upon the polarity of the impulse placed upon the line circuit.

For example, the relay CK⁰ in the control office is energized from (B-), through polar contact 70 of relay L⁰ in a right hand position, wire 65 71, back contact 72 of relay SL⁰, wire 73, windings of checking relay CK⁰, to (CN). The current which flows in this circuit causes the relay CK⁰ to actuate its polar contact to a left hand position.

70 Similarly, the relay CK at the field station is energized from (B+), through polar contact 74 of line relay L in a right hand position, wire 75, back contact 76 of relay SL, wires 77 and 78, windings of checking relay CK, to (CN). The current which flows in this circuit causes the

relay CK to actuate its polar contacts to right hand positions.

After the predetermined time has elapsed required for the picking up of the contacts of the relay SL⁰ and SL in the control office and at the field station respectively, the system is then in readiness to be sequentially and synchronously stepped through a control cycle of operation, as the polarity of the initial impulse placed upon the line circuit during this period is positive in character. This fact is registered in the two position polar checking relays CK⁰ and CK, so that after the relays SL⁰ and SL have once been energized the nature of the cycle of operation is determined or fixed. 10 15

In the control office, the checking relay CK⁰ completes a stick circuit for the selecting relay S⁰, so that the selecting relay S⁰ will remain energized throughout the cycle even after the opening of back contact 48 which is included 20 in its pick-up circuit. This stick circuit is closed from (+), through back contact 79 of stepping relay d, wire 80, polar contact 81 of checking relay CK⁰ in a left hand position, wire 82, front contact 83 of selecting relay S⁰, wires 84 25 and 50, windings of selecting relay S⁰, to (-).

It might happen that the preceding cycle of operation was for the transmission of indications, in which case the contacts of the checking relay CK at the field station would be in left 30 hand positions at the beginning of this cycle of operation under consideration. Thus, upon the

picking up or actuation of the polar contact 74 of the line relay L to a right hand position in response to the initial energization of the line, energy is momentarily placed on the upper winding of the selecting relay S. As the checking relay CK is of the two position polarized type, while the selecting relay S is of the neutral type, the contacts of the checking relay CK respond 40 much more quickly than the contacts of a neutral, relay, which prevents the application of energy to the upper winding of the relay S for a length of time sufficient to actuate the contacts of this selecting relay. 45

As soon as the slow-acting relays SL⁰ and SL have actuated their contacts to picked up positions, the stepping relay banks in the control office and at the field station take the first step. For example, the stepping relay 1 at the field 50 station is energized by a pick-up circuit from (+), through front contact 85 of relay SL, wire 86, front contact 87 of relay LR, wire 88, polar contact 89 of relay HS in a left hand position, wire 90, back contacts 91 and 92 of stepping 55 relays 4 and 2 respectively, wires 93 and 94, windings of stepping relay 1, to (-). As soon as the contacts of the stepping relay are picked up, a stick circuit is closed for this relay from (+), through front contact 85 of relay SL, wires 95 and 96, front contact 97 of stepping relay 1, 60 wires 98 and 94, winding of relay 1 to (-).

As the pick-up and stick circuits of the stepping relay a in the control office are substantially identical with those of the stepping relay 65 1, such circuits will not be pointed out in detail.

The picking up of the contacts of the stepping relay a in the control office completes an energizing circuit for the impulsing relay IM from (+), through back contacts 100, 101 and 102 of 70 stepping relays d, c and b respectively, front contact 103 of stepping relay a, wire 104, lower winding of impulsing relay IM, wire 105, polar contact 106 of relay HS⁰ in a right hand position, wire 107, front contact 108 of relay SL⁰, to (-). The 75

energization of the impulsing relay IM causes its back contact 15 to be actuated to an open position which deenergizes the line circuit.

When the contacts of the polar relays L⁰ and L assume their neutral biased positions, such conditions are in turn repeated by the quick-acting line repeating relays LR⁰ and LR.

The dropping of the contacts of the relay LR⁰ in the control office causes the energizing circuit 10 of the relay HS⁰ to be closed, which receives the application of current of opposite polarity by a circuit from (B-), through front contact 38 of stepping relay a, back contacts 39, 40 and 41 of stepping relays b, c and d respectively, 15 wire 42, windings of relay HS⁰, wire 43, back contact 44 of quick-acting line repeating relay LR⁰, to (CN). The current which flows in this circuit causes the half step relay HS⁰ to actuate its polar contacts to left hand dotted line positions. 20 Similarly, the polar contact 89 of relay HS is actuated to an opposite position at this time with the relay LR deenergized, as will be obvious from the drawings.

The movement of polar contact 106 of relay 25 HS⁰ to a left hand position opens the energizing circuit for the impulsing relay IM, so that the contact 15 of this relay IM then assumes a deenergized position for energizing the line circuit with an impulse having a polarity determined 30 in accordance with the position of the polar contact 52 of code sending relay CS⁰.

During the time subsequent to the deenergization of the line repeating relay LR⁰ but prior to the actual closing of back contact 15, the code 35 sending relay CS⁰ is energized with current of a polarity determined in accordance with the control desired to be transmitted upon the next step. For example, on this step with the contacts of the stepping relay a picked up, the code 40 sending relay CS⁰ is energized with current of a polarity dependent upon the position of the switch machine control lever SML. If the switch machine control lever SML is in a left hand normal position, current of positive polarity from 45 (B+) is applied to this code sending relay; but, if the lever SML is in a right hand reverse position, current of negative polarity from (B-) is applied to this code sending relay. Thus, a circuit is closed from (B+) or (B-), through lever 50 contact 109 in a left or right hand position respectively, wire 110, front contact 16 of stepping relay a, back contacts 17, 18 and 19 of stepping relays b, c and d respectively, wire 20, front contact 55 21 of field starting button FSB, wire 22, back contact 23 of relay LR⁰, wire 24, windings of code sending relay CS⁰, to (CN). This application of potential to the code sending relay CS⁰ causes the actuation of its polar contact to a proper position for determining the desired polarity of the 60 next impulse applied to the line circuit upon the closure of back contact 15 of impulsing relay IM. As the relay HS⁰ must be actuated to a new position and the relay IM dropped away before the contact 52 of relay CS⁰ is effective, there 65 is a sufficient margin of time to insure that it has properly responded.

Upon the closure of back contact 15, the line relays L⁰ and L are then energized with current of a polarity dependent upon the position of 70 contact 52, but irrespective of the particular polarity of the impulse, the quick-acting line repeating relays LR⁰ and LR are energized and their contacts are immediately picked up.

Immediately upon the picking up of the contacts of the relay LR at the field station, the

impulse storing relay IS is energized with positive or negative current dependent upon whether the impulse applied to the line circuit is positive or negative in character. For example, depending upon whether the impulse is positive or negative, an energizing circuit for relay IS is closed from (B+) or (B-), through polar contact 74 of line relay L in a right or left hand position, wire 75, front contact 76 of relay SL, wire 111, front contact 112 of relay LR, wire 113, back contact 114 of selecting relay S, wire 115, windings of relay IS, to (CN). The current which flows in this circuit actuates the polar contact of relay IS to a right or left hand position depending upon whether it is positive or negative 15 in direction, and the contact remains in such position in readiness for the execution of the message during the following deenergization of the line circuit.

This energization of the line repeating relays 20 LR⁰ and LR causes the second stepping relays to be energized. For example, the stepping relay 2 has a pick-up circuit closed from (+), through front contact 85 of relay SL, wire 86, front contact 87 of relay LR, wire 88, polar contact 89 of 25 relay HS in a right hand position, wire 116, back contact 117 of stepping relay 3, front contact 118 of stepping relay 4, wires 119 and 120, windings of stepping relay 2, to (-). As soon as the contacts of stepping relay 2 pick up, a stick circuit is 30 closed from (+), through front contact 85 of relay SL, wires 95, 121 and 122, front contact 123 of stepping relay 2, wires 124 and 120, windings of stepping relay 2, to (-).

In a similar manner, the stepping relay b in 35 the control office is picked up and stuck up.

The picking up of the stepping relay b closes an energizing circuit for the impulsing relay IM from (+), through back contacts 100 and 101 of stepping relays d and c respectively, front contact 40 102 of stepping relay b, wire 125, upper winding of impulsing relay IM, wire 126, polar contact 106 of relay HS⁰ in a left hand position, wire 107, front contact 108 of slow-acting line repeating 45 relay SL, to (-). The impulsing relay thus energized actuates its contact 15 to a picked up position opening the line circuit, the deenergization of which is repeated in the control office and at the field station by the line relays L⁰ and L respectively, which is in turn repeated by the relays 50 LR⁰ and LR.

An execution circuit closed during this period of time in which the line circuit is deenergized and the stepping relay 2 is picked up, governs the switch machine control relay SMR. This is 55 accomplished by the application of positive or negative potential upon the relay SMR in accordance with whether a positive or negative impulse is stored in the impulse storing relay IS, as determined by the preceding energization of the line circuit in accordance with the position of the control lever SML. For example, the relay SMR is energized from (B+) or (B-), through polar contact 127 in a right or left hand position, wire 128, back contact 129 of selecting relay S, wire 130, back contact 131 of relay LR, wire 132, front contact 133 of relay SL, wire 134, back contacts 135 and 136 of stepping relays 4 and 3 respectively, front contact 137 of stepping relay 2, wire 138, 70 windings of relay SMR, to (CN). The current which flows in this circuit actuates the polar contact of the relay SMR to a right or left hand position depending upon whether positive or negative potential respectively is applied thereto.

With polar contact 139 of the switch machine control relay SMR in a right hand position, positive potential (+) is applied to the normal operating wire N of the switch machine SM; but with 5 polar contact 139 of the switch machine control relay SMR in a left hand position, positive potential (+) is applied to the reverse operating wire R of the switch machine SM. This energization of the normal and reverse wires N and R results 10 in the corresponding operations of the switch machine SM for moving the track switch TS to normal or reverse locked positions in the usual manner.

In brief, the positioning of the control lever 15 SML determines the polarity applied to the switch machine control relay SMR, which in turn governs the operation of the switch machine. Obviously, if the control lever is moved to a new 20 position, the track switch will be operated; but if it is left in a former position during a cycle of operation, the track switch will remain in such former position.

During this deenergized period of the line with the relay LR⁰ deenergized, the relay HS⁰ receives 25 current of the opposite polarity from (B+) through front contact 39 of stepping relay b; and similarly the contact 89 of relay HS is actuated to a new position. Also, simultaneously therewith, the code sending relay CS⁰ is energized in 30 accordance with the position of the contact 140 of signal lever SGL to determine the polarity of the next impulse applied to the line circuit upon the closure of back contact 15 of the impulsing relay IM. The polarity of such impulse is then 35 made effective upon the deenergized period of the third step to govern the signal relay SR. In other words, the step-by-step operation of the stepping relay banks occurs sequentially and in synchronism for as many steps as required to transmit the 40 control conditions to the field station. In this case, the relays SR and DR, for controlling the signals at the field station, are controlled upon the third and fourth steps respectively in accordance 45 with the position of the control lever SGL in a similar manner as explained for the relay SMR.

This transmission of controls, as above explained in detail, may be briefly considered by saying that the code sending relay CS⁰ is positioned during each deenergized period of the line 50 for determining the character of the next impulse, while the character of such next impulse is stored in the impulse storing relay IS for execution during the succeeding deenergization of the line circuit, to the particular function control relay, such 55 as relay SMR, for which it is designated.

This transmission of controls continues until the predetermined number of steps have been taken, which, by way of example, has been specifically illustrated as including four steps, only 60 three of which are employed for control impulses, as the application of the first impulse to the line circuit is employed for initiation purposes and determining the particular character of the operating cycle, thus initiated.

When the last stepping relay is picked up in the control office, stepping relay d in this case, a circuit is completed for the impulsing relay IM through front contact 100, which circuit is maintained 70 until the line circuit has been deenergized for a predetermined period of time to mark off the end of that cycle of operation, thereby opening front contact 108 of relay SL⁰. More specifically, the picking up of front contact 41 of stepping relay d fails to place current of the oppo-

site polarity on the relay HS⁰ upon the deenergization of the relay LR⁰, so that the energizing circuit for the impulsing relay IM is not broken by the operation of polar contact 106 to an opposite position, as usually occurs on the preceding 5 steps.

The picking up of the contacts of the relay d also causes the deenergization of the selecting relay S⁰ by opening its stick circuit at open back contact 79 allowing its contacts to drop away. 10

The deenergization of the line circuit is repeated by the quick-acting line repeating relays LR⁰ and LR, as previously, but in this case the deenergized condition of the line continues until a sufficient length of time is marked off for the contacts of the relays SL⁰ and SL to drop away, as their energizing circuits are respectively opened at front contacts 64 and 65. Although the relays SL and SLR pick up together, the relay SLR adds its drop-away time to the drop-away time of the relay SL, as its energizing circuit includes, besides front contact 66 of relay LR, the front contact 141 of relay SL. In other words, the release or drop-away time of the relays LR, SL and SLR at the end of an operating cycle are cumulative for 15 reasons hereinafter pointed out. 20

The drop away of the relay SL⁰ in the control office and the relay SL at the field station causes the dropping away of the stepping relays at both 25 locations, and the return of the system to a normal condition of rest. The drop away of the relay SL⁰ in the control office permits the selecting relay S⁰ to be again picked up providing the starting button SB is actuated by the operator 30 for initiating another such cycle of operation for the transmission of control impulses; while the drop away of the relay SLR at the field station permits the selecting relay S to be picked up providing a new indication has occurred causing the 35 energization of the relay CHS for initiating a 40 cycle for the transmission of indication impulses.

Transmission of indications.—Whenever the system is in the period of blank it may be initiated from a field station either in response to some 45 automatic change in traffic conditions, or in response to the operation of a traffic controlling device manually governed from the control office when such device is caused to assume a new position.

For example, the operation of the track switch TS from a normal position to a reverse position, in response to the control of lever SML, as above explained, deenergizes the relay WP during such reverse operation, but energizes it with current of 50 the opposite polarity at the completion of such 55 operation. The deenergization of the relay WP as well as its reenergization momentarily deenergizes the stick circuit of the change relay CH during the movement of contact 34 from a front to a back contacting position, or vice versa. As 60 the change relay CH is of the relatively quick-acting type this momentary deenergization is of sufficient duration to allow the contacts of the change relay to drop away, permanently opening the stick circuit of this relay until it is again energized, or resensitized so to speak, by energization of its pick-up circuit.

The change relay may also be deenergized upon the change of traffic conditions, as for example 70 the deenergization of the track relay T upon the passage of a train over the associated detector track circuit, when the traffic controlling devices have been properly governed for the movement of traffic in accordance with the usual practices.

In brief, the stick circuit for the change relay 75

CH is carried through front and back contacts of the relay WP and the track relay T, and may similarly be carried through like contacts of other traffic controlling devices associated with

- 5 this field station. Irrespective of the particular change which occurs, the deenergization of the change relay CH closes a pick-up circuit for the change storing relay CHS, which in turn energizes the pick-up circuit of the change relay as
 10 well as energizing the initiating circuit of the selecting relay S.

Assuming that the system is at rest, and that a change in indication conditions is incurred by the deenergization of the track relay T, for ex-

- 15 ample, then the CHS relay is energized by a circuit from (+), through back contact 32 of track relay T, wire 33, front contact 34 of relay WP, wire 35, back contact 36 of change relay CH, wire 142, upper winding of relay CHS, to (-).
 20 The relay CHS, thus energized, actuates its contacts to picked up positions, thereby closing its stick circuit from (+), through back contact 150 of relay S, wires 151, 152 and 153, front contact 154 of relay CHS, wire 155, lower winding of
 25 relay CHS, to (-). This circuit also has (+) applied to wire 152 through back contact 156 of stepping relay 2.

- The pick-up circuit for the relay CH is now closed from (+), through back contacts 150 and 30 156 of relays S and 2, respectively in multiple, wires 152 and 157, front contact 158 of relay CHS, wire 159, upper windings of relay CH, to (-). The closure of the front contacts of relay CHS also completes a pick-up circuit for the relay S, as the system is at rest, from (+), through front contact 160 of relay CHS, wire 161, back contact 162 of relay SLR, wires 163 and 164, lower winding of relay S, to (-).

- 35 The picking up of the contacts of the relay S 40 in response to this energization accomplished by the relay CHS, closes front contact 58 of relay S, so as to place a positive impulse upon the line circuit from the battery FB in accordance with the normal position assumed by the polar contact of the relay CS during the normal at rest condition of the system. This line circuit is closed from the positive terminal of the battery FB, through polar contact 165 of relay CS in a right hand position, wire 166, front contact 58 45 of relay S, wire 57, windings of relay L, line wire 12 to the control office, back contact 15 of relay IM, wire 56, windings of relay L⁰, wire 55, back contact 54 of relay S⁰, wire 167, to the common wire 10 thence to the mid tap of battery FB at 50 the field station.

- 55 Although this impulse is termed a positive impulse, its actual direction is opposite to the direction of current flow set up by a positive impulse from the tower battery TB, so that the contacts 60 of the polar relays L⁰ and L are actuated to left hand dotted line positions. However, for convenience in the description, this may be considered as a positive impulse, as the polarities on contact 70 65 10 of relay L⁰ are so arranged that a corresponding potential is applied to the execution circuits for the indication storing relays IR (with suitable exponent). Thus, a circuit is completed from (B-), through polar contact 74 in a left hand position, wire 75, back contact 76 of relay SL, wires 77 and 78, windings of relay CK, to (CN). The current flow in this circuit actuates the contacts of the relay CK to left hand positions. This further insures that the relay S is picked up by reason of a circuit closed from (B-), through 75 polar contact 74 of relay L in a left hand position,

wire 75, back contact 76 of relay SL, wires 77 and 168, polar contact 169 of relay CK in a left hand position, wire 170, upper winding of relay S, to (CN).

Similarly, in the control office the actuation 5 of the contacts of the relay L⁰ by current flowing in the line circuit, as above pointed out, energizes the relay CK⁰, by a circuit from (B+), through polar contact 70 of relay L⁰ in a left hand position, wire 71, back contact 72 of relay SL⁰, wire 10 73, windings of relay CK⁰, to (CN). Current flowing in this circuit actuates the polar contact 81 to a right hand position.

The energization of the line circuit, as indicated by the relays L⁰ and L, is repeated by the 15 quick-acting line repeating relays LR⁰ and LR immediately, while a predetermined time thereafter, the energization of the respective slow-acting relays SL⁰ and SL is effective to pick up their contacts. During the time subsequent to 20 the picking up of the contacts of the relays L⁰ and L, the relays CK⁰ and CK are controlled as above pointed out, so that upon the picking up of the contacts of the relays SL⁰ and SL, the character of the cycle has been determined or 25 registered by these checking relays, and the system is in readiness for taking the first step.

Upon the picking up of the contacts of relay SL, a stick circuit is closed from (+), through front contact 171 of relay SL, wire 172, polar contact 173 of relay CK in a left hand position, wire 174, front contact 175 of relay S, wires 176 and 164, lower winding of relay S to (-). As the relays SL and SLR have practically the same slow-acting characteristics, they are energized or 30 picked up at practically the same time, so that the pick-up circuits of the relay S are opened at substantially the same time. However, for the purpose of preventing a momentary deenergization of the relay S, the front contact 171 of relay 35 SL is preferably closed before the back contact 176 of the relay SL is opened.

With the relays SL⁰ and SL at the control office and field station respectively energized, pick-up and stick circuits are closed for the first 40 stepping relays, as previously pointed out.

The picking up of the stepping relay a in the control office effects the energization of the impulsive relay IM, which in turn opens back contact 15 and deenergizes the line circuit, as previously explained. This condition is repeated by 50 the line relays L⁰ and L, as well as by the relays LR⁰ and LR.

During this deenergized condition of the line circuit, the code sending relay CS at the field 55 station is energized with current of a polarity in accordance with the energized or deenergized condition of the relay WP. For example, if the track switch is locked, the relay WP is energized and (B+) is applied to this relay CS; while on the other hand, if the track switch TS is unlocked, the relay WP is deenergized and (B-) is applied to this relay CS. This energizing circuit for the relay CS is closed from (B+) or (B-), through front or back contact 177 respectively of relay WP, wire 178, front contact 25 of stepping relay 1, back contacts 26, 27 and 28 of stepping relays 2, 3 and 4 respectively, wire 29, back contact 30 of relay LR, wire 31, windings of relay CS, to (CN). 60 65 70

In either case, the relay CS is energized with current of a particular polarity as soon as the contacts of the relay LR drop away and prior to the time of the closure of back contact 15 upon the drop away of this contact subsequent to the 75

deenergization of the relay IM. In other words, the relay CS is controlled simultaneously with the actuation of the contacts of the half step relays HS⁰ and HS to new positions, in a manner similar 5 to that explained for the relay CS⁰ in the control office during a control cycle of operation.

The response of the relay HS⁰ deenergizes the relay IM, so as to energize the line circuit, as above explained.

- 10 Thus, dependent upon the energized or deenergized position of the relay WP, the line circuit receives positive or negative potential from the battery FB. A positive impulse actuates the polar contacts of relays L⁰ and L to left hand positions; 15 while a negative impulse actuates the polar contacts of these relays to right hand positions. But, irrespective of the particular polarity placed upon the line circuits, it is repeated by their respective quick-acting line repeating relays LR⁰ and LR causing the next step to be taken both in the control office and at the field station.

The particular polarity of this line circuit impulse is stored in the control office in the impulse storing relay IS⁰ by the energization of 25 this relay with positive or negative current from (B+) or (B-) depending upon the character of the impulse on the line circuit, through polar contact 70 of line relay L⁰ in left or right hand positions respectively, wire 71, front contact 72 of relay SL⁰, wire 180, front contact 181 of relay LR⁰, wire 182, back contact 183 of relay S⁰, wire 184, windings of the relay IS⁰, to (CN).

It is to be noted that the impulse storing relay IS at the field station is not responsive to these 30 energizations of the line circuit during an indication cycle of operation, as its controlling circuit is opened at the back contact 184 of relay S. This condition corresponds to the unresponsiveness of the relay IS⁰ to control impulses on the 35 line circuit by reason of open back contact 183 of relay S⁰ during a control cycle of operation.

This energization of the line relays L⁰ and L repeated by the relays LR⁰ and LR also effects the picking up of the stepping relays b and 2 at 40 the control office and at the field station. The picking up of the stepping relay b causes in the control office the energization of the impulsing relay IM and the picking up of contact 15 which again deenergizes the line circuit. This condition is in 45 turn repeated by the various line repeating relays.

The deenergization of the line relay LR⁰ closes a circuit for the indication storing relay IR¹, so that the message or indication temporarily stored in the impulse storing relay IS⁰ may be executed, 50 or permanently stored in the relay IR¹ until a new indication is transmitted. For example, depending upon whether the relay IS⁰ was energized with current of positive or negative polarity during the energized condition of the line, (B+) 55 or (B-) is applied through polar contact 190 of relay IS⁰ in a right or left hand position respectively, wire 191, back contact 192 of relay S⁰, wire 193, back contact 194 of relay LR⁰, wire 195, back contacts 196 and 197 of stepping relays d and c 60 respectively, front contact 198 of stepping relay b, wire 199, windings of relay IR¹, to (CN). The application of positive potential (B+) to relay IR¹ actuates its contacts to left hand positions; while the application of negative potential (B-) 65 to relay IR¹ actuates its contacts to right hand positions.

In other words, depending upon whether the relay WP is energized or deenergized, current of one polarity or the other is placed upon the relay 70 CS during one deenergized period of the line circuit.

circuit which determines the polarity of the following energized period of the line, this particular polarity being stored in the impulse storing relay IS⁰. Then the relay IR¹ is energized upon the following deenergized period of the line in accordance with the particular polarity stored in the relay IS⁰. In brief, an indication started on one deenergized period of the line reaches its destination, so to speak, upon the following deenergized period of the line circuit.

It may be noted in this connection, that the indication storing relays IR (with suitable exponent) cannot be energized during a control cycle of operation, as the back contact 192 of the selecting relay S⁰ is open. This condition corresponds to a similar condition set up at the field station during an indication cycle of operation, as now being described, which condition prevents the energization of the function control relays, such as relays SMR, SR and DR, by reason of open 10 back contact 129 of selecting relay S.

During this deenergized period of the line circuit with the second stepping relays b and 2 picked up, and simultaneous with the energization of the indication storing relay IR¹ in accordance with the position of contact 190 of relay IS⁰, the code sending relay CS at the field station is being positioned in accordance with the next indication to be transmitted. In this case, the relay CS is controlled in accordance with the normal or reverse position of the track switch TS as indicated by the relay WP. For example, if the track switch is in a normal position, the relay CS is energized with current of positive polarity (B+); while if the track switch TS is in a reverse position, the relay CS is energized with current of negative polarity (B-). In other words, dependent upon the position of the track switch TS, the relay CS is energized from (B+) or (B-), through polar contact 202 of relay WP in a right hand or left hand position respectively, wire 203, front contact 26 of stepping relay 2, back contacts 27 and 28 of stepping relays 3 and 4 respectively, wire 29, back contact 30 of relay LR, wire 31, windings of code sending relay CS, to (CN).

Also, simultaneously with the actuation of the code sending relay CS at the field station and the indication storing relay at the control office, the half step relays HS⁰ and HS are suitably positioned, as previously described.

The response of the half step relay HS⁰ results in the deenergization of the impulsing relay IM closing back contact 15 and thereby energizing the line circuit with a polarity in accordance with the position of contact 165 of the code sending relay CS in the field, which is now positioned in accordance with the normal or reverse position of the track switch TS as indicated by the polar contact 202 of relay WP.

The energization of the line circuit results in the picking up of the third stepping relays c and 60 3, as well as the energization of the impulsing relay IM. However, prior to the energization of the relay IM, the impulse storing relay IS⁰ is energized in accordance with the polarity of the impulse applied to the line circuit, as previously described.

Thus, upon the deenergization of the line circuit, the indication storing relay IR² is energized in accordance with the position of the polar 70 contact 190 of relay IS⁰; while at the field station, the code sending relay CS is being positioned in accordance with the next indication to be transmitted. The response of the half step relays HS⁰ and HS conditions the system for the next energi- 75

zation of the line circuit by deenergizing the relay IM.

In a similar manner, as above explained, the step-by-step operation continues, and an indication is transmitted on each step, until a sufficient number of steps have been taken to transmit such indications as may be desired. In this case, a system has been illustrated as having only three indication transmitting steps, but it is to be understood that the system may be readily extended to include as many indication steps as may be found necessary in actual practice.

When the system has taken the last step (fourth in the present embodiment), the line circuit is maintained deenergized for a sufficient period of time to allow the drop away of the contacts of the slow-acting relays SL^0 and SL . This is by reason of the continued energization of the impulsing relay IM on the fourth step, due to the absence of the application of current of the opposite polarity to the half step relay HS^0 through contact 41, as explained in connection with the control cycle of operation. The deenergization of the slow-acting relays SL^0 and SL causes the dropping away of the stepping relay banks and the selecting relay S, together with the positioning of the various other relays to their normal positions.

Assuming the track switch TS to be in a normal position during such cycle of operation, positive impulses will be placed upon the first and second indication steps so that the indication storing relays IR^1 and IR^2 will both receive positive impulses. This positions their respective polar contacts 210 and 211 in left hand positions to complete a circuit for the normal indicator NI from (+), through polar contact 210 of relay IR^1 in a left hand position, wire 212, polar contact 211 of relay IR^2 in a left hand position, normal indicator NI, to (-). Thus, the operator is informed of the normal position of the switch TS.

On the other hand, if the track switch TS is in a reverse position, a negative impulse will be transmitted on the second step and the indication storing relay IR^2 will be energized with a negative potential actuating its contact 211 to a right hand position. This causes the energization of the reverse indicator RI through a circuit obvious from the drawings.

In the event that the track switch TS is unlocked and the relay WP is deenergized, a negative impulse will be transmitted upon the first step resulting in the application of negative potential to the indication storing relay IR^1 which actuates its polar contact 210 to a right hand position. This applies potential from (+), through polar contact 210 in a right hand position, lock indicator LI, to (-). The energization of this indicator displays to the operator that the track switch TS is unlocked.

If on the third step the track relay T is energized, a positive impulse will be transmitted actuating the polar contact 213 of the indication storing relay IR^3 to a left hand position; while if the track relay T is deenergized, a negative impulse will be transmitted actuating the polar contact 213 of relay IR^3 to a right hand position. With polar contact 213 in a right hand position, positive potential from (+) is applied to the indicator OS advising the operator of the presence of a train on the associated detector track section.

It is to be understood of course that although merely indicator lamps have been illustrated for advising the operator of the conditions at the

field station, other suitable indicator means such as audible warnings, miniature movable track switch points, or the like, may be employed as desired.

Indication cycle initiated from the control office.—Inasmuch as the indications of the traffic conditions along the trackway may occur at any time and are not under the control of the operator, it may happen that such a change will occur simultaneously with the actuation of the starting button SB for the transmission of controls from the control office. The present invention provides special means for such a case, so that the system may be set into operation irrespective of the locked up condition initially brought about under these circumstances.

It may also happen that for one reason or another, the operator may desire to check the conditions of the apparatus and traffic indications at the field station, so as to be sure that he is setting up the proper routes. Under these circumstances, there may be no automatic change in conditions at the field station to initiate the system into operation, so that a manual act upon the part of the operator is required to start the system in a special way in order to accomplish an indication cycle of operation.

These various operating conditions will probably be best understood by a description of typical cases.

Let us assume that the system is at rest and that the operator desires to check the indication conditions as now set up at the field station. To do this, he actuates the field starting button FSB to a depressed position. This manual manipulation is effective to energize the selecting relay S^0 and to simultaneously apply negative potential to the code sending relay CS^0 . Inasmuch as the code sending relay CS^0 is of the two position polarized type, while the relay S^0 is of the neutral type, the code sending relay CS^0 responds more quickly and its polar contact 52 assumes a left hand position in readiness for placing a negative impulse upon the line circuit prior to the closure of front contact 54 of relay S^0 .

More specifically, negative potential is applied to relay CS^0 by a circuit from (B-), through back contact 21 of lever FSB, wire 22, back contact 23 of relay LR^0 , wire 24, windings of code sending relay CS^0 , to (CN). Energy is applied to the pick-up circuit of the selecting relay S^0 from (+), through back contact 200, wires 201 and 47, back contact 48 of relay SL^0 , wires 49 and 50, windings of relay S^0 , to (-).

The picking up of contact 54 of the relay S^0 subsequent to the response of the polar contact 52 of relay CS^0 places a negative impulse on the line circuit, that is, it causes current to flow in the line circuit in a direction which corresponds to the direction of current flow set up whenever the system is initiated into a cycle of operation automatically from the field station. Therefore, the polar contacts of the line relays L^0 and L are actuated to left hand positions, which conditions are, of course, repeated by their respective quick-acting line repeating relays LR^0 and LR as well as by their respective slow-acting line repeating relays SL^0 and SL , all in the usual manner as above described.

However, during the time subsequent to the actuation of the polar contacts of the line relays to left hand positions, but prior to the picking up of the contacts of the slow-acting line repeating relays SL^0 and SL , the respective checking relays CK^0 and CK are energized with polar-

ties corresponding to those applied when the system is initiated automatically from the field station. For example, in the control office, (B+) will be connected to the relay CK⁰ through 5 polar contact 70 in a left hand position, and back contact 72 of relay SL⁰, thereby causing its contact 81 to be actuated to a right hand dotted line position; while at the field station, (B-) will be connected to the relay CK through polar 10 contact 74 of relay L in a left hand position and back contact 76 of relay SL, thereby causing its polar contacts 169 and 173 to be actuated to left hand positions.

With contact 169 of relay CK in a left hand 15 position and polar contact 74 of relay L in a left hand dotted line position, (B-) is connected to the upper winding of the selecting relay S, through a circuit previously described, until the contacts of the slow acting relay SL are 20 picked up. This application of current to the relay S actuates its contacts to picked up positions, and in so doing the positive terminal of the field battery FB is connected to the line circuit through front contact 58 and polar contact 25 165 of relay CS in a right hand position.

It is noted, that the negative terminal of the battery TB is also connected to the line circuit and that the potentials of these batteries TB and FB are additive, thereby increasing the line current to substantially double its normal value. Although, it would not be particularly desirable to maintain such a condition of high current value in the line circuit for a protracted period of time, the actual period of time during which 30 this condition exists, that is, during the pick-up period of the slow-acting relay SL⁰ plus the drop-away period of the relay S⁰, is in practice not usually more than one second. Also, the line relays are so constructed as to be unharmed by 35 this initial current value.

Upon the picking up of the contacts of the relay SL⁰ in the control office, the pick-up circuit of the selecting relay S⁰ is opened at back contact 48, allowing the contacts of relay S⁰ to drop away, as its stick circuit is not completed 40 with polar contact 81 of relay CK⁰ in a right hand position. The closure of back contact 54 of relay S⁰ removes the negative terminal of the tower battery TB from the line circuit, so that 45 a normal current value is established in the line circuit by the field battery FB.

At the field station the picking up of the contacts of the relay SL opens the pick-up circuit of the relay S at back contact 76 but closes its stick circuit through front contact 171, polar contact 173 of relay CK in a left hand position, and front contact 175 of relay S, as previously 50 described.

In other words, the same conditions are established in the control office and at the field station as when an automatic initiation of the system occurs at the field station, so that with the selecting relay S⁰ in the control office deenergized, and the selecting relay S at the field station energized or picked up, the system is then 55 in readiness to transmit its indications without further manual intervention but in the usual way, as previously described.

It will be noted, that during the initiation of 60 the system under the above circumstances, the line circuit is momentarily interrupted by the changing of the contact 58 of relay S from a back point to a front point, and similarly by the changing of the contact 54 of relay S⁰ from a 65 front point to a back point, but these moment-

tary interruptions are of such relatively short duration that they are not repeated by the line relays L⁰ and L.

It is believed that the resulting cycle of operation for the transmission of indications will be 5 readily understood by reference to the cycle of operation already described.

As above mentioned, it may happen that the operator actuates the starting button FSB at the same time that the change storing relay CHS 10 is picked up. In such a case, the selecting relays S⁰ and S are simultaneously energized, and their contacts assume picked up positions at substantially the same time, thus connecting the positive terminals of both the battery TB and 15 FB to the line circuit through their respective front contacts 54 and 58. The potentials of the two batteries oppose each other so that there is no resulting current flow in the line circuit, and the system remains in a static condition. The 20 operator noticing this condition, either because of the failure to receive proper indications, or by reason of a special operation indicator such as shown, for example, in the patent to W. D. Hailes et. al. No. 2,170,141 issued August 22, 25 1939, actuates the field starting button FSB to a depressed position which reverses the polarity applied to the code sending relay CS⁰. This actuates the polar contact 52 of relay CS⁰ to a left hand position connecting the negative terminal 30 of the battery TB to the line circuit, so that there is a resulting current flow in the line circuit in a direction corresponding to that current flow established by an automatic initiation from the field station, which current flow is of substantially double the normal current flow, as the potentials of these batteries are 35 additive. In other words, the same conditions are now set up as if the operator had originally 40 actuated the field starting button FSB.

More specifically, this direction of current flow in the line circuit is registered by the relays CK⁰ and CK so that upon the picking up of the relays SL⁰ and SL, the pick-up and stick circuits of the relay S⁰ will be opened, while the stick circuit for 45 the relay S will be maintained closed. After the slow-acting relays have picked up their contacts, the first stepping relays are picked up and the cycle of operation continues for the transmission of indications in the usual way. When the second 50 step is taken the selecting relay S being picked up, the relay CHS is deenergized, as the back contacts 150 and 156 are both open.

It will be noted, that the field starting button FSB is of the self-restoring type, so that the operator must hold it in an actuated position until the slow-acting relays SL⁰ and SL have been energized for a sufficient time that their contacts will 55 assume picked up positions. In actual practice, this time period is so short that the operator does not find it necessary to actuate the button FSB for an undue length of time. If, in some cases, it is found that the operator does not have time or fails to actuate the button FSB for a sufficient period of time, automatic means can be supplied 60 to maintain this starting condition until the relay SL⁰ is picked up, but as this is a special manual operation required only in unusual cases, such 65 automatic means is not considered as ordinarily required.

It is believed unnecessary to describe in detail the resulting transmission of indications during the cycle initiated, as just described, but it will be pointed out that at the end of the operating cycle, the operator may cause the next cycle of opera- 75

tion to be a control cycle, irrespective of the fact that some other change may have occurred at the field station which would normally cause the next cycle to be an indication cycle. This function of the system is accomplished more particularly by reason of the added release time of the relay SLR over or beyond the drop away time of the contacts of the relay SL.

- More specifically, after the operator has actuated the field starting button FSB to cause the operation of the system in the event of a simultaneous start from the control office and from the field station and has again released the button FSB, when the system has started, he immediately actuates the starting button SB and continues to hold it in an actuated position. This actuation of the starting button SB is not effective during the resulting cycle of operation, as the back contact 48 of relay SL⁰ is open.
- Upon the dropping away of the contacts of the relays SL⁰ and SL at the end of such cycle of operation, however, the selecting relay S⁰ is immediately picked up, which places a positive impulse upon the line circuit because the code sending relay CS⁰ has been returned to its normal position even prior to the drop away of the stepping relay contacts. This is accomplished by reason of a circuit which is completed for this code sending relay CS⁰ as soon as the last step has been taken and the line circuit deenergized with the back contact 23 of relay LR⁰ closed. This circuit is closed from (B+), through front contact 19 of stepping relay d, wire 20, front contact 21 of field starting button FSB, wire 22, back contact 23 of relay LR⁰, wire 24, windings of relay CS⁰, to (CN).

In other words, at the end of the indication cycle of operation, the relay SL drops away in the usual manner, deenergizing the selecting relay S, but the relay SLR does not drop away until a predetermined time after the contacts of the relay SL are in deenergized positions, which prevents the relay S from being again picked up for a prolonged period of time, even if the relay CHS is energized. During this prolonged period of time, the relay S⁰ in the control office may be picked up, which, with the code sending relay CS⁰ returned to a normal position, places a positive impulse upon the line circuit for initiating the system from the control office, thereby causing a control cycle of operation and preventing the initiation from the field station.

The field station cannot interfere in such a case, as the positive impulse is repeated by the relays L and LR prior to the drop away of the contact 162 of the relay SLR, which prevents the contacts of the relay SLR from assuming deenergized positions.

Such an initiation of a control cycle is registered by the relays CK⁰ and CK, and the system continues to function for the transmission of controls in a manner similar to that already described. If desired, the operator may transmit controls for as many cycles as conditions may warrant without the interruption by the field station, and during such time the change storing relay CHS, if there are indications to be transmitted, will remain picked up because its stick circuit has not been opened at the back contact 150 of the relay S.

Summary.—In general, the system of centralized traffic control contemplated by this invention is particularly adapted for interconnecting a control office and a single outlying field station, irrespective of the number of devices to be controlled at that station or the number of devices

having indications to transmit to the control office. This system is characterized by the fact that the communication is established between the control office and the outlying field station over only two line wires with the line circuits normally deenergized while the system is at rest. 5

The present invention also provides suitable means whereby only controls or indications may be transmitted during any one particular operating cycle, together with means for initiating a 10 cycle for controls in the control office; for automatically initiating the cycle of indications at a field station; or for manually initiating a cycle for indications in the control office. In other words, although the system is normally at rest, it 15 may be initiated into operation for transmission of messages in either direction under every condition which is normally encountered in practice.

The system of the present invention employs a tower battery and a field battery for supplying impulses of distinctive polarities to the line circuits for transmitting the messages. Such an arrangement means a definite and positive response which is a distinct advantage for a system of this character. 20 25

Various other features of the system, embodying the present invention may be said to reside in the detail circuits and devices of the system.

Having thus described a centralized traffic control system as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention, except as limited by the appended 30 35 40 claims.

What I claim is:

1. In a remote control system for railroads, a control office, a field station, a line wire extending from said control office to said field station, a return line wire extending from said control office to said field station, a line relay at said control office and at said field station included in series with said line wire, a normally closed impulsive contact included in series with said line wire, a selecting contact at said control office for normally connecting said line wire to said return line wire, a selecting contact at said field station for normally connecting said line wire to said return line wire, means at said control office for connecting a battery between said line wire and said return line wire when said selecting contact at said control office is picked up, means at said field station for connecting a battery between said line wire and said return line wire when said selecting contact at said field station is picked up, means at said control office for intermittently opening said impulsive contact when either one of said selecting contacts is picked up, and means responsive to the alternate energization and deenergization of said line relays when a selecting contact is picked up and said impulsive contact is being opened and closed. 45 50 55 60 65 70

2. In a remote control system of the selector type; the combination with a control office and a field station; of a single line circuit connecting said control office with said field station; step-by-step means at said control office and 75

at said field station responsive to series of impulses on said line circuit to operate through cycles of operation irrespective of their character; battery sources at said control office and 5 at said field station; selecting means for initially connecting said battery sources in said line circuit with a particular polarity, whereby when said sources at said control office and at said field station are both connected in said line circuit there 10 is no current flow; impulsive means at said control office for opening said line circuit when there is a current flow in said line circuit for a pre-determined time and for opening said line circuit at time spaced intervals thereafter, whereby a 15 plurality of impulses are placed on said line circuit to comprise a cycle of operation; code sending means at the control office and at said field station for determining the polarity of each impulse except the first, said code sending means 20 at said control office or at said field station being chosen by said selecting means, whereby messages are transmitted to and from said field station and said control office during separate cycles 25 of operation; and means manually operable to reverse the polarity of the initial connection of said source in said control office.

3. In a remote control system comprising two stations connected by a single line circuit, transmitting means at each station for delivering series of code elements to said line circuit, means at one station for time spacing the code elements of each series irrespective of which transmitting means is effective, means at each station for imparting a different character to the first element of each such series originating at that station, and means at each station responsive to the character of said first element of a series to render ineffective the transmitting means at such station when the character of the first element is determined at the other station.

4. In a remote control system comprising two stations connected by a single line circuit, transmitting means at each station for delivering series of code impulses to said line circuit, means at one station for time spacing the code impulses of each series irrespective of which transmitting means is effective, means at each station for imparting a particular polarity to the first impulse of each series originating at that station, and means at each station responsive to the polarity of said first impulse to render effective or ineffective the transmitting means at such station, depending upon the polarity of such first impulse.

5. In a remote control system for railroads, a plurality of stations connected by a single line circuit, transmitting means at each station including a source of current for impressing a series of distinctive impulses on said line circuit, means at one station for time spacing the code impulses of each series irrespective of which transmitting means is effective, means at each station for always marking the first impulse of a series transmitted from that station, with a character different from the first impulse transmitted from another station, storing means at each station registering the character of the first impulse of each series of impulses impressed on said line circuit, and means controlled by said storing means for determining the direction of transmission over said line circuit.

6. In a remote control system for railroads, a plurality of stations connected by a line circuit, means at each station for impressing a series of positive and negative impulses on said

line circuit, means at each station determining the polarity of the first impulse of a series transmitted from that station, storing means at each station registering the polarity of the first impulse of each series of impulses impressed on said line circuit, and means controlled by said storing means when the first impulse of a series is of one polarity to cause the transmission over said line circuit to be in one direction but when the first impulse of a series is of the other polarity to cause the transmission over said line circuit to be in the opposite direction.

7. In a remote control system for railroads, a plurality of stations connected by a line circuit having a different series of positive and negative impulses impressed thereon, a slow acting relay at each of said stations picked up at the beginning of each series and dropped at the end of that series, a two-position polar relay at each station, means controlled in accordance with the polarity of the first impulse of each series only during the pick-up period of said slow acting relay at that station at the beginning of that series for distinctively controlling said polar relay to thereby render each station either responsive or unresponsive to the remaining impulses of that series.

8. In a remote control system, a control office, a field station, a line wire and a return line wire extending from said control office to said field station, a line relay at said control office and at said field station included in series with said line wire, a normally closed impulsive contact included in series with said line wire, a selecting contact at said control office for normally connecting said line wire to said return line wire, a selecting contact at said field station for normally connecting said line wire to said return line wire, means at said control office for selectively and reversibly connecting a battery between said line wire and said return line wire when said selecting contact at said control office is picked up, means at said field station for selectively and reversibly connecting a battery between said line wire and said return line wire when said selecting contact at said field station is picked up, means at said control office for intermittently opening said impulsive contact when either one of said selecting contacts is picked up, and means selectively responsive to the direction of energization and the alternate de-energization of said line relays when a selecting contact is picked up and said impulse contact is being opened and closed.

9. In combination with a plurality of switching devices at a field station, a single line circuit connecting the field station with a control office, means at the control office for energizing said line circuit with impulses of positive and/or negative characters to transmit control signals over said line circuit to said devices for effecting the control thereof, means at the field station for energizing said line circuit with impulses of positive and/or negative characters to transmit indication signals over said line circuit from said devices to the control office for indicating the positions thereof, means at the control office for time spacing all impulses on said line circuit irrespective of their direction of their transmission, means for distinctively characterizing a portion of said control and said indication signals in accordance with the required direction of their transmission over said line circuit, and means responsive to the character of said portion of

said signals for selecting the direction of transmission over said line circuit.

10. A centralized railway traffic controlling system of the multiple impulse type for transmitting distinctive electrical impulses over a line circuit connecting two spaced stations comprising, a first station, a second station, a line circuit connecting said stations, a series of stepping relays at each station, an impulsive relay at said first station controlled by the series of stepping relays at that station for successively opening and closing said line circuit to define impulses of current in said line circuit, a plurality of control devices at said second station, a polarity determining relay at said second station controlled by the series of stepping relays and said devices at said second station for determining the polarity of each impulse, a neutral relay at each station repeating the impulses on said line circuit irrespective of their polarity for controlling the series of stepping relays at the corresponding station, a plurality of controlled relays at said first station, a polar relay at said first station responsive to the polarity of each current impulse, and a circuit for each controlled relay controlled by a front contact of one of the stepping relays at said first station and by a contact of said polar relay and in accordance with the position of the corresponding control device.
30. 11. A centralized railway traffic controlling system of the multiple impulse type for transmitting distinctive electrical impulses over a line circuit connecting two spaced stations comprising, a first station, a second station, a line circuit connecting said stations, a series of stepping relays at each station, an impulsive relay at said first station controlled by the series of stepping relays at that station for successively opening and closing said line circuit to define impulses of current in said line circuit, a plurality of control devices at said second station, a polarity determining relay at said second station controlled by the series of stepping relays and said devices at said second station for determining the polarity of each impulse, means for causing said polarity determining relay to remain in its condition during a particular impulse irrespective of the condition of said stepping relays until said impulsive means has terminated such impulse, a neutral relay at each station repeating the impulses on said line circuit irrespective of their polarity for controlling the series of stepping relays at the corresponding station, a plurality of controlled relays at said first station, a polar relay at said first station responsive to the polarity of each current impulse, and a circuit for each controlled relay controlled by a front contact of one of the stepping relays at said first station and by a contact of said polar relay and in accordance with the position of the corresponding control device.
60. 12. In a remote control system, a control office, a field station, a line circuit connecting said control office with said field station, means for intermittently and distinctively energizing said line circuit from a source of current in said control office to provide a series of distinctive impulses, means for intermittently and distinctively energizing said line circuit from a source of current at said field station to provide an additional series of distinctive impulses, means for distinctively characterizing the first impulse of each series, and means governed by the character of the first impulse of a series to determine the source of current to be used for the succeeding impulses of said series.

13. A remote control system of the synchronous type for transmitting controls and indications between a control office and a field station over the same line circuit comprising, a source of current in the control office and another source of current at the field station for energizing said line circuit, means in the control office for intermittently opening and closing said line circuit, a series of stepping relays at the control office and at the field station operated sequentially one at a time in response to the energization and deenergization of said line circuit, means in the control office governed by its stepping relays and at times effective during each deenergization of the line for determining the condition of energization of said line circuit from the source of current in the control office in accordance with the controls to be transmitted, means at the field station governed by its stepping relays and effective at other times during each deenergization of the line circuit to determine the next succeeding condition of energization of said line circuit from the source of current at the field station, and means in the control office and at the field station responsive to the condition of energization of said line circuit at the other end for registering indications and controls respectively.

14. A remote control system of the character described for transmitting indications from a station to a control office over a line circuit comprising, means at the control office effective when set into operation to intermittently open and close said line circuit, stepping relays at the control office and at the field station operated sequentially one at a time in response to the energization and deenergization of said line circuit, a battery in the field station, means at the field station controlled by its stepping relays and effective during each deenergization of the line circuit for determining the polarity of the next connection of said battery to said line circuit, means in the control office governed by its stepping relays and responsive to the polarity of energization of said line circuit for each step.

15. In a remote control system, a receiver in a control office comprising a line relay, a series of contacts adapted to be closed one at a time in sequence in response to repeated operation of the line relay by a series of impulses of current, means at a field location for imparting a particular character to selected ones of said impulses, a series of indication relays in said control office one for each impulse, and means for consecutively actuating each of said indication relays, each when one of said contacts becomes closed, to a position in accordance with the character of the next preceding impulse.

16. In a remote control system, a receiver in a control office comprising a line relay, a series of contacts adapted to be closed one at a time in sequence in response to repeated operations of the line relay by a series of impulses of current, means at a field location for imparting a particular character to selected ones of said impulses, a series of indication relays in said control office, one for each impulse, and means rendered effective at the termination of each impulse for actuating the corresponding indication relay to a position determined by the character of said impulse.

17. In a remote control system; a single line circuit connecting a control office and a field station; normally-at-rest transmitting means at the control office and at the field station, each of which transmitting means is capable of being

initiated into operation to transmit a series of distinctive impulses over said line circuit; receiving means at the control office responsive to a series of distinctive impulses on said line circuit transmitted from said field station; receiving means at the field station responsive to a series of distinctive impulses on said line circuit transmitted from said control office; manually controlled initiating means at the control office for initiating the transmitting means at the control office into operation; automatic initiating means at the field station for initiating the transmitting means at the field station into operation; lock-out means permitting only one of said transmitting means to be initiated into operation to transmit a series of impulses during any given time and in the event of substantially simultaneous actuation of said initiating means at the control office and at the field station permitting only said transmitting means at the field station to operate to transmit a series of distinctive impulses; and means allowing said transmitting means at the control office to be initiated into operation by said manually controlled initiating means immediately following any series of impulses irrespective of the presence of another automatic initiation at the field station.

18. In a remote control system, a circuit having different series of time spaced impulses of distinctive characters impressed thereon, control relay means included in said circuit and operable to distinctive positions to correspond with the distinctive characters of said impulses, a slow acting relay, an energizing circuit for said slow acting relay closed during each impulse on said circuit by said control relay means irrespective of the distinctive character of such impulse so as to cause said slow acting relay to be picked up during the first impulse of any series and to remain picked up until after the last impulse of any series, a storing relay of the polarized electromagnetic stick type, and energizing circuit means for said storing relay energized with one polarity or the other in accordance with the distinctive position assumed by said control relay means only during the pick up period of said slow acting relay, whereby the character of the first impulse of any series is stored by said storing relay.

19. In a remote control system; a control office and a distant field station; a line circuit connecting the control office and field station to form a normally deenergized closed loop; step-by-step means at the control office and at the field station, each responsive to a series of impulses on said line circuit to operate through a cycle of operation; sources of current at said control office and at said field station, said sources being of substantially equal potentials; initiating means at the control office for inserting said control office source in said line circuit to cause its initial energization in a particular direction; initiating means at the field station for inserting said field station source in said line circuit to cause its initial energization in a direction opposite to said particular direction; impulsing means rendered active by the initial energization of said line circuit in either direction to open and close said line circuit to impress a series of time spaced impulses on said line circuit from the particular source then inserted in the line circuit; transmitting means at the control office and at the field station, each being effective on the successive steps of its said step-by-step means only when its source is inserted in said line circuit to determine the polarity of each successive impulse

of the ensuing series in accordance with messages to be transmitted; and receiving means at the control office and at the field station, each being responsive on the successive steps of its step-by-step means only when its transmitting means is ineffective to determine the polarity of the impulses for such steps; whereby the simultaneous insertion of both said sources into said line circuit by said control office and field station initiating means fails to energize the line circuit and thereby fails to render active said impulsing means. 5

20. In a normally-at-rest remote control system; a control office and a field station; a line circuit connecting said control office with said field station and comprising a normally closed deenergized loop; a source of current at the control office and another source of current at the field station; field station initiating means for at times inserting the source of current at said field station into said loop circuit to effect its initial energization; control office initiating means for at other times inserting said source at the control office into said loop circuit to effect its initial energization; means at the control office responsive to the initial energization of said line circuit for intermittently opening and closing said loop circuit so as to cause said line wires to be energized by time spaced impulses irrespective of the particular one of said sources inserted in said loop circuit; step-by-step means in the control office and at the field station operated step-by-step in synchronism in response to the energization and deenergization of said line wires; indication transmitting means at the field station controlled by its step-by-step means during each deenergization of said line wires to determine the polarity of the next succeeding energization of said line wires from said source at said field station when said field station initiating means has inserted such source into said loop circuit; means at the control office governed by its step-by-step means and responsive to the polarity of energization of said line wires after each step when said field station indication transmitting means is operating; control transmitting means at the control office controlled by its step-by-step means during each deenergization of said line wires to determine the polarity of the next succeeding energization of said line wires from its said source when said control office initiating means has inserted such source into said loop circuit; and means at the field station governed by its step-by-step means and responsive to the polarity of the energization of said line wires after each step when said control transmitting means is operating. 10 20 25 30 35 40 45 50 55 60

21. In a remote control system; a line circuit connecting a control office and a field station to form a normally deenergized closed conducting loop; step-by-step means at the control office and at the field station, each responsive to a series of impulses on said line circuit to operate step-by-step through a cycle of operation; a source of current at the control office and another source at said field station, said sources being of substantially equal potentials; manually controlled initiating means at the control office for inserting said control office source into said line circuit to cause its initial energization in a particular direction; automatic initiating means responsive to a change in the condition of any one of a plurality of devices at the field station for inserting said field station source into said line circuit to cause its initial energization 70 75 80 85 90

- gization in a direction opposite to said particular direction; impulsing means rendered active by the initial energization of said line circuit in either direction to open and close the line circuit to impress a series of time-spaced impulses on such line circuit; transmitting means at the control office and at the field station each being effective on the successive steps of its said step-by-step means only when its source is inserted in said line circuit to determine the polarity of each successive impulse of the ensuing series in accordance with messages to be transmitted; receiving means at the control office and at the field station, each being responsive to the successive steps of its step-by-step means to the polarity of the impulses for such steps only when its transmitting means is ineffective to determine the polarity of the impulses for such steps; and manually operable means for controlling said initiating means at the control office to cause the insertion of said control office source into said line circuit in a direction opposite to said particular direction; whereby the operation of said manually operable means upon the simultaneous insertion of both said sources into said line circuit by the simultaneous operation of said control office and said field station initiating means causes said impulsing means to be initiated into operation and renders the transmitting means at the field station effective by reason of the energization of the line circuit being in the same direction as the energization automatically caused by the initiating means at the field station.
- 35 22. In a remote control system; a single line circuit forming a normally closed deenergized conducting loop arranged to connect a control office and a field station; step-by-step means at the control office and at the field station operated step-by-step in response to a series of impulses on said line circuit; a source of current at the control office and another source at the field station, said sources being of substantial equal potentials; manually controlled initiating means at the control office for inserting said control office source into said line circuit to cause its initial energization in a particular direction; automatic initiating means at the field station for inserting said field station source in said line circuit to cause its initial energization in a direction opposite to said particular direction; impulsing means rendered active by the initial energization of said line circuit in either direction to open and close said line circuit to impress a series of time-spaced impulses on said line circuit; cycle demarking means at the control office and at the field station rendered active in response to the initial energization of said line circuit so as to simultaneously mark the beginning of such series of impulses at the control office and at the field station at substantially the same time, but arranged to mark the end of such series at the control office and at the field station successively in that order, said cycle demarking means at the control office and at the field station respectively controlling their initiating means so as to allow the respective initiating means to become effective only when such cycle demarking means is inactive; transmitting means at the control office and at the field station each being effective on the successive steps of the step-by-step means only when its source is inserted in said line circuit to determine the polarity of each successive impulse of the following series of impulses in accordance with mes-
- sages to be transmitted; receiving means at the control office and at the field station each being responsive to the polarity of the impulses on the line circuit on the successive steps of its step-by-step means only when its transmitting means is ineffective during such steps; and manually operable means for controlling the initiating means at the control office to cause the insertion of said control office source into said line circuit to cause its initial energization in a direction opposite to said particular direction to thereby effect the initiation of the system into operation for transmission from the field station to the control office; whereby messages are transmitted from the field station to the control office during one cycle of operation upon the simultaneous operation of the initiating means at the control office and at the field station with the system being available for a cycle of operation for the transmission of messages from the control office to the field station on the next following cycle of operation although the initiating means at the field station is automatically operated to initiate another cycle of operation for the transmission of messages from the field station to the control office by reason of said control office and said field station initiating means becoming successively effective upon the return of said cycle demarking means to inactive conditions.
- 30 23. In a remote control system, a plurality of locations including a control office and a field station, two line wires extending between said control office and said field station, sources of electrical energy located at said control office and at said field station, means at said control office and at said field station for normally connecting said two line wires in a deenergized loop circuit, means at said control office and other means at said field station, each means for connecting the source at the corresponding location into said loop circuit, selective means determining which source shall be connected into said loop circuit at any one time, means in said loop circuit at said control office for opening and closing said loop circuit at time spaced intervals when a source is included therein to cause its energization, step-by-step means at said control office and at said field station responsive to take one step for each energization of said loop circuit; means at each location controlled by the step-by-step means at its location when that one of said locations has its source included in said loop circuit as determined by said selective means, to be rendered effective during each deenergization of said loop circuit to determine the polarity with which the source at such location is connected in said loop circuit; and means at each location controlled by the step-by-step means at its location when the other of said locations is determining the polarities of the energizations of said loop circuit.
- 35 24. In a remote control system of the selector type; the combination with a control office and a field station, each having a source of current; of a single line circuit connecting said control office with said field station; step-by-step means at said control office and at said field station responsive to series of impulses on said line circuit to operate through cycles of operation irrespective of their character; selecting means for energizing said line circuit from the source at said control office or from the source at said field station, said selecting means energizing said line circuit from only one of the sources during any 40
- 45 50 55 60 65 70 75

- given cycle of operation; impulsing means at said control office alone for opening and closing said line circuit at time spaced intervals, whereby a plurality of impulses are placed on said line circuit to cause a cycle of operation of said step-by-step means; and code sending means at said control office and at said field station controlled through contacts of their respective step-by-step means for determining the polarity of the impulse for each step, said code sending means at said control office or at said field station being chosen by said selecting means for any given cycle of operation, whereby messages are transmitted to and from said field station and said control office during separate cycles of operation, and whereby the time spacing of said messages is determined wholly in said control office.

25. In a normally-at-rest remote control system, a control office and a field station connected by two line wires forming a normally deenergized

loop circuit, a source of current at the field station, means at the field station for initiating the system into operation by inserting said source into said loop circuit to effect its energization, means in the control office for intermittently 5 opening said loop circuit so that said line wires are energized by time spaced impulses from said source, step-by-step means in the control office and at the field station operating step-by-step in response to the energization and deenergization 10 of said line wires, means at the field station controlled by its step-by-step means and effective during each deenergization of said line wires to determine the distinctive character of the next succeeding energization of said line wires from 15 said source, and means in the control office governed by its step-by-step means for responding to the distinctive character of the energization of said line wires after each step.
